DISPLAY SIGN

George H. Evans, Washington, D. C., assignor of
one-half to Richard K. Stevens, Washington,
D. C.

Application January 26, 1939, Serial No. 252,976

32 Claims. (Cl. 40—133)

This invention relates to advertising signs and more particularly to those signs which have movable mediums associated therewith to increase the attraction of the sign.

It is well known that advertising signs or displays have an increased attracting power by the incorporation of various movable means and elements to gain the attention of the passer-by. Many designs and arrangements have been used in an effort to provide an attractive motion effect, but these arrangements have frequently proven impracticable due to their cost of construction and/or operation and because of their frequent failure to function.

Accordingly, it is an object of the present invention to provide a display having motion effects associated therewith which are extremely attractive and greatly enhance the value thereof. In addition, it is contemplated that these movable effects may be produced at a relatively low cost and operated at a minimum. Furthermore, while the motion effects greatly enhance the display, they are produced with a minimum number of parts which are arranged so as to substantially overcome the effects of wear and tear.

Briefly, an advertising sign may be provided with twisted elongated reflecting members which may be supported by suspension with a minimum of friction and inertia so that they may be easily rotated by a suitable source of power. The reflecting member may be suspended on a ball race and the lower end thereof positioned in any suitable manner so as to provide a minimum of friction.

The source of power may be in the form of a wind, heat or electric motor. The wind motor may comprise a curved vaned member which may be secured to the shaft of the rotatable reflector by a friction coupling which supplants the use of a governor to maintain the reflector member at a relatively constant speed regardless of the speed of the wind motor. In the event an electric motor is preferred, a relatively small motor which is driven by batteries, may be connected by a loose coupling to the lower end of the suspended shaft supporting the reflector member. Further, illumination may be provided to increase the brilliancy of the reflected light designs and the suspended reflectors may be rotated by the heat generated by the illuminating means.

The invention both as to its organization and method of operation, together with additional objects and advantages thereof, will best be understood from the following description of the

specific embodiments when read in connection with the accompanying drawings, wherein like reference characters indicate like parts throughout.

Figure 1 is a view in perspective of a display embodying the principles of the present invention and operated by a wind motor;

Figure 2 is a view in cross section of the supporting and coupling means for the reflector members used in the display;

Figure 3 is a view in elevation of an electric motor and coupling for driving the reflector member used in the display;

Figure 4 is a view in cross-section of modified supporting and coupling means used in conjunction with an electric motor;

Figure 5 is a view in perspective of a heat motor arranged to operate the reflector member used in the display, said heat motor having self-adjustable vanes to regulate the speed thereof; and

Figure 6 is a view in cross-section of a vane used in the heat motor shown in Figure 4.

Referring specifically to Figure 1, a display may be mounted on the corner of a building such as a gasoline station or the like and may comprise a reflector member 1 supported within a frame 2 with an upper end portion 3 and a lower end portion 3'. The reflector member 1 may be of the type disclosed in my application for patent Serial Number 236,349 and may be associated with an optically effective screen, if desired, as disclosed in my application for patent Serial Number 216,361. The reflector 1 may be mounted on a shaft 4 which may be supported within suitable bearings 5 and 5', carried by the end portions 3 and 3'. This reflector may be rotated by any suitable source of power such as a wind motor 7 which may be mounted above the upper end portion 3 and supported by a shaft 8. The shaft 8 may be coupled with the reflector shaft 4 in any convenient manner. Flood lights 6 or other means for illumination may be located within the frame 2 in any desirable arrangement so as to produce the most attractive effect.

As better shown in Figure 2, the reflector 1 supported by the shaft 4 may be connected to the shaft 8 supporting the wind motor 7 by a coupling 9. The shaft 4 is suspended from the coupling by a brass collar 10 secured to the upper end thereof as with a set screw 11. This brass collar is beveled at its lower side 12 and is adapted to snugly rest within the beveled wall 13 of a hardened steel collar 14 having a central aperture 15 therein to freely receive the shaft 4. The

hardened steel collar 14 is retained within a cup 16 as by a set screw 17, and said cup 16 may be secured to the lower extremity of the shaft 8 as by a set screw 18. The shaft 8 may be floatingly 5 mounted by a collar 20 which may be secured to said shaft by a set screw 21, said collar having its lower surface 22 beveled so as to snugly rest within the upper ring 23 of a ball race 24. The lower ring 25 of the ball race 24 may be comprised by the upper flange of a channel shaped frame 25' supported within the upper end portion 3, and may be provided with an aperture 26 in the lower portion of said frame 25' to freely pass the shaft 8. The shaft 8 is thereby prevented 10 from wobbling when strong air currents strike the wind motor 7.

The above described construction comprises a floating suspension support for the movable members and the friction coupling between the 20 source of power and reflector 1 precludes the necessity of providing more complicated and expensive mechanism such as a governor. By centrally suspending the shafts in the ball race 24, friction and inertia is reduced to a minimum 25 so that the various parts may be operated with the smallest possible power source. The lower end of the reflector shaft 4 may be loosely positioned by any suitable type of bearing 5' so as to cause as little friction as possible. In addition, 30 the friction coupling 9 provides a relatively governed speed for the reflector member 1 due to the fact that at slower speeds the shaft 4 will turn uniformly with the shaft 8, but at higher speeds slippage will occur. Regardless of the 35 speed of the wind motor 7 the reflector 1 will be rotated at a relatively constant speed. It is important that the reflector 1 be maintained at a relatively constant speed not to exceed a certain maximum in order to obtain the most attractive and desirable effect.

It is to be noted that the above described construction is extremely simple in design and incorporates a minimum number of parts. Consequently, continuous operation of the movable 45 parts without difficulty is virtually assured. Furthermore, by forming one of the friction collars of hardened steel, which will substantially completely resist wear, and the other of brass, the continuous smooth working of the friction coupling is also assured. Whereas the hardened 50 steel collar strongly resists wear and tear, the brass collar will consequently wear down evenly so that binding and inoperation of the friction coupling will be prevented.

55 The wind motor 7 may comprise a relatively simple arrangement consisting of a single sheet having its opposed ends curved in opposite directions to form vanes 28 and 29. This provides a concave and convex vane on each side of the 60 motor, the concave vane being effective to offer the greatest resistance to the air currents and the convex vane being effective to offer the least resistance thereto. Accordingly, the air currents striking the concave vane will cause the motor 7 65 and shaft 8 to rotate, the convex vane offering but slight resistance in passing the air currents off to the side, thereby permitting said rotation to take place. The vanes of the wind motor may be colored or otherwise treated to enhance their 70 attractiveness so that they, too, may cooperate in gaining attention to the display or sign. It has been found, for instance, that coloring one side of the vanes white and the other side black or with other contrasting colors the wind motors 75 themselves form a very attractive display and

add considerably in gaining attention to the unit.

In addition to the above described means for rotating the reflector 1, an electric motor may be used to drive said reflector if desired. In view of the fact that signs using a display of the type 5 described may be positioned throughout the countryside and frequently where electricity is not available, it is desirable to use very small 10 motors which may be operated by batteries, if necessary. Furthermore, if electricity is accessible, the cost of operation of these motors is so small that this feature is a negligible 15 consideration. As the reflectors are fairly large and of considerable wind resistance and inertia, it is necessary to mount the reflectors and couple them to the electric motor so as to reduce the resistance and inertia to a minimum, thereby permitting the large reflectors to be driven by the very small motors.

To accomplish this object, the reflectors may 20 be suspended as above described with the exception that the friction coupling 9 is omitted, that is, the beveled collar 10 may be made to assume the position occupied in Figure 2 of the drawings by the beveled collar 20 so that the 25 reflector 1 and shaft 4 will be suspended directly from the ball race 24. This provides a floating suspension support which permits the reflector to be easily rotated by the very small motors. In order to provide free movement of the reflector 1, the lower end of the shaft 4 may be 30 freely coupled with the drive of the electric motor, thereby eliminating the necessity of a bearing which would increase the friction resistance.

Accordingly, as shown in Figure 3, the lower 35 end of the shaft 4 may be pronged to form a fork 30 having prongs 31 which extend parallel to the axis of the shaft 4 and preferably equidistant therefrom. The prongs 31 may be loosely received within apertures 32 extending through a drive wheel 43 mounted upon the drive shaft 34 of the motor 35. This motor 35 may be a synchronous motor of well known type such as is used in electric clocks and the like and connected 40 by leads 36 to a source of electric current such as a battery (not shown) or the like. These motors are provided with lugs 37 extending from the sides thereof which may be secured to supporting blocks 38 as by screws 39, the blocks 38 45 being secured to the lower end portion 3' of the frame 2 of the display. By this arrangement the relatively small synchronous motor is amply strong to rotate the floatingly mounted reflector at a substantially constant speed.

The motor 35 is shown as including a gear reduction box 35' so as to reduce the speed of the drive shaft 34 to any desired number of revolutions per minute. It may be desirable to further reduce the cost of producing one of these signs 60 by using an electric motor without the gear reduction means. In this event, the electric motor may be secured to a drive mechanism similar to that shown in Figure 2. As shown in Figure 4, an electric motor 40 may be mounted in the upper end portion 3 and have its shaft 41 extending downwardly through an aperture 42 in said end portion. A coupling 43 may be secured to the shaft 41 which closely resembles the hereinbefore described coupling 9. This coupling may comprise a cup member 46 secured to the shaft 41 by the set-screw 18 and contain a ball-race 44. The lower ring 45 of the ball-race 44 may be secured in the cup 46 by the set-screw 17 and the upper ring 46 may support the beveled collar 10 which 70

is fixed to the reflector shaft 4 by the set-screw 11. By such an arrangement the reflector 1 may be rotated at a relatively slow and constant speed regardless of the speed of the electric motor 40 due to the resistance offered by the reflector 1 and the relatively small drive force of the frictional engagement offered by the ball-race 44 and the beveled collar 10.

Still another means for driving the reflector 1 may comprise a heat motor such as shown in Figure 5. This arrangement is preferably used in a display unit wherein the frame 2 is enclosed by means of optically effective transparent panels 50 such as prismatic or lenticulated glass, and means for illumination is contained therein such as flood lights 9. The heat motor may be mounted on a shaft 51 which may be coupled to the reflector shaft 4 in one of the above described manners or may comprise an extension thereof. In either event the shaft 4 may be suspended by a cone-bearing 20 to which the shaft 51 may be connected and the whole assembly suspended in the ball-bearing 24 (not shown). The heat motor may comprise an inner disc 52, secured to the shaft 51, a plurality of vanes 53, and an outer ring 54. The vanes may be pivotally mounted on shafts 55 which extend radially from the inner disc 52 to the outer ring 54.

By the use of these pivotally mounted vanes 53 the necessity of a governor or other speed regulating device is eliminated as said vanes 53 will automatically adjust themselves according to the speed of rotation and the force of the rising heat waves. As best shown in Figure 6, these vanes 53 may be formed in two sections, a depending section 57 and a somewhat narrower upper section 58 which is positioned at an angle with respect to the depending section 57. When at rest the depending vanes 57 lie in a 45° plane and the upper vane 58 is horizontal. As the heat waves, indicated by the arrow A, arise to strike the depending vane section 57, it acts to pivot said vane upwardly but due to the weakness of the initial heat waves and the counteraction thereof on the vanes 58, including their counterbalance, the motor is rotated in the direction of the arrow A' instead. As the force of the heat increases it would normally act to speed up rotation of the motor; however, by the present arrangement the force of the heat waves will strike the substantially horizontal upstanding vane 58 to pivot it upwardly and the increased air resistance met by the whole vane 53 will tend to swing the depending vane back to the position shown in broken lines, thereby increasing the resistance and decreasing the efficiency of the force of the heat waves. Consequently, this motor will rotate at a substantially constant speed.

From the foregoing description it will be readily understood that many factors may enter into the arrangements for regulating the speed of rotation of the reflector 1 which vary according to the type of construction and surrounding circumstances. For instance, the area and/or force of the frictional engagement may be varied by the type of contact. Likewise, the weight of the suspended element and the size and/or shape of the reflector are important factors. In addition, the type of regulator must be adjusted according to the medium surrounding the suspended element and the consequent resistance offered thereby. For instance, the resistance may be considerably greater when the element is suspended to the open air than when suspended within an enclosed housing or less than when suspended

within a liquid wherein the viscosity of the liquid may comprise a governing feature. Furthermore, the variable speed and power of the source of motivation form deciding factors in selecting the means for regulating the speed of rotation of the reflector 1.

The reflector 1 may comprise a relatively large, elongated member which is twisted about its longitudinal axis, and may be formed of metal foil such as aluminum foil or the like. In addition, the surfaces of the reflector may be crumpled or otherwise formed to present a plurality of reflecting faces. This reflector 1 may be mounted along its axis upon a relatively light weight shaft 4 which may comprise a wire or the like. While this shaft 4 may be slightly flexible and of insufficient strength to rigidly support the reflector 1 in an upright position, it is strong enough to support said reflector by suspension. Such an arrangement permits a light weight construction, which reduces friction and inertia to a minimum. Consequently, large display units may be driven by motors of relatively low power. This feature is particularly important when electric motors are employed as battery operable motors may be used. These motors may be of 2 watt and 3.2 watt type.

Although the reflector 1 has been described as an elongated metal foil strip twisted about its longitudinal axis, it will be readily understood that other types and formations of reflectors or movable members may be substituted therefor and still remain within the essence of the invention. Many different effects may be produced by the use of various types of reflectors or display elements as above described and in the manner in which they are employed and/or driven. In constructing a sign according to the present invention, the type of display element to be incorporated therein may be chosen according to the type of matter to be advertised, the location of the sign with respect to its surroundings, and the location of the sign with respect to the observers.

Although certain specific embodiments of the present invention have been shown and described, many modifications thereof are possible, and the present disclosure should be construed only in an illustrative sense. The present invention, therefore, is not to be restricted except insofar as is necessitated by the prior art and by the spirit of the appended claims.

I claim:

1. A display unit comprising a support, a display element, frictional means for movably suspending said display element solely at the top thereof from said support, and a source of power for moving said display element.

2. A display unit comprising a support, a display element, frictional means for rotatably suspending said display element solely at the top thereof from said support, and a source of power for rotating said display element.

3. A display unit comprising a support, a display element, frictional means for rotatably suspending said display element solely at the top thereof from said support, a source of power for rotating said display element, and means for coupling said suspended display element to said source of power.

4. A display unit comprising a support, a display element, means for rotatably suspending said display element from said support, a source of power for rotating said display element, and means for coupling said suspended display ele-

- ment to said source of power, said coupling means being adapted to substantially regulate the speed of rotation of said display element regardless of the speed of said source of power.
- 5 5. A display unit comprising a support, a display element, means for rotatably suspending said display element from said support, a source of power for rotating said display element, and a friction coupling connecting said suspended display element to said source of power, said friction coupling being adapted to substantially regulate the speed of rotation of said display element.
- 10 6. A display unit comprising a support, a display element comprising a reflector, frictional means for rotatably suspending said display element solely at the top thereof from said support, and a source of power for rotating said display element.
- 15 7. A display unit comprising a support, a display element comprising an elongated reflector twisted about its longitudinal axis, frictional means for rotatably suspending said display element solely at the top thereof from said support, and a source of power for rotating said display element.
- 20 8. A display unit comprising a support, a relatively large display element comprising an elongated reflector twisted about its longitudinal axis and mounted upon a relatively light-weight shaft, means for rotatably suspending said display element solely at the top thereof for said support, and a source of power for rotating said display element.
- 25 9. A display unit comprising a support, a relatively large display element comprising an elongated reflector twisted about its longitudinal axis and mounted upon a flexible shaft, means for rotatably suspending said display element solely at the top thereof from said support, and a source of power for rotating said display element.
- 30 10. A display unit comprising a support, a relatively large display element comprising an elongated reflector twisted about its longitudinal axis and mounted upon a relatively light-weight flexible shaft, means for rotatably suspending said display element solely at the top thereof from said support, and a source of power for rotating said display element.
- 35 11. A display unit comprising a support, a display element, means for rotatably suspending said display element solely at the top thereof from said support, and an air-current operated motor for rotating said display element.
- 40 12. A display unit comprising a support, a display element, means for rotatably suspending said display element solely at the top thereof from said support, and a wind-operated motor for rotating said display element.
- 45 13. A display unit comprising a support, a display element comprising a reflector, means for rotatably suspending said display element solely at the top thereof from said support, and a heat operated motor for rotating said display element.
- 50 14. A display unit comprising a support, a display element, frictional means for rotatably suspending said display element solely at the top thereof from said support, and an electrically operated motor for rotating said display element.
- 55 15. A display unit comprising a support, a display element, frictional means for rotatably suspending said display element solely at the top thereof from said support, a source of power for rotating said display element, and a light source for illuminating said display element.
- 60 16. A display unit comprising a support, a display element comprising a reflector, means for rotatably suspending said display element solely at the top thereof from said support, a heat operated motor for rotating said display element, 5 and a light source for illuminating said display element and generating heat to operate said motor.
- 65 17. A display unit comprising a support, a display element comprising a reflector, means for rotatably mounting said display element on said support, a heat operated motor for rotating said display element, said motor comprising a plurality of self-adjusting vanes whereby to regulate the speed of rotation of said motor according to the force of the heat waves and air resistance.
- 70 18. A display unit comprising a support, a relatively large display element comprising an elongated reflector twisted about its longitudinal axis and mounted upon a relatively light-weight flexible shaft, means for rotatably suspending said display element from said support, a source of power for rotating said display element, and a friction coupling connecting said suspended display element to said source of power, said friction coupling means being adapted to substantially regulate the speed of rotation of said display element.
- 75 19. A display unit comprising a support, a relatively large display element comprising an elongated reflector twisted about its longitudinal axis and mounted upon a relatively light-weight flexible shaft, means for rotatably suspending said display element from said support, a heat operated motor for rotating said display element, said motor comprising a plurality of self-adjusting vanes whereby to regulate the speed of rotation of said motor according to the force of the heat waves and air resistance, a friction coupling connecting said suspended display element to said motor, said friction coupling means being adapted to substantially regulate the speed of rotation of said display element, and a light source for illuminating said display element and generating heat to operate said motor.
- 80 20. A display unit comprising a support, an optically effective screen mounted thereon, a display element comprising a reflector located behind said screen to direct light rays therethrough, frictional means for rotatably suspending said display element solely at the top thereof from said support, and a source of power for rotating said reflector.
- 85 21. A display unit comprising a support, a display element comprising a reflector formed of metal foil, frictional means for rotatably suspending said display element from said support, and a source of power for rotating said display element.
- 90 22. A display unit comprising a support, a display element, frictional means for rotatably and adjustably suspending said display element solely at the top thereof from said support, and a source of power for rotating said display element.
- 95 23. A display unit comprising a support, a display element, a source of power for rotating said display element, frictional means associated with said support for rotatably and adjustably supporting said display element and said source of power, and coupling means for suspending said display element solely at the top thereof.
- 100 24. A display unit comprising a support, a display element, a source of power for rotating said display element, frictional means associated with said support for rotatably and adjustably supporting said display element and said source of power.

- power, and friction coupling means for suspending said display element solely at the top thereof.
25. A display unit comprising a support, a display element, frictional means for rotatably suspending said display element from said support, a source of power for rotating said display, and means associated with the lower end of said suspended display element for coupling said element to said source of power.
- 10 26. A display unit comprising a support, an aperture in said support, a display element including a support member, and a tapered bearing attached to the support member of said display element so that the tapered wall of said bearing faces said display element, the tapered wall of said bearing being seated in said aperture in said support with the support member extending through said aperture so that said display element is thereby suspended.
- 20 27. A display unit comprising a support, an aperture through said support including a bearing, a display element including a support member, and a tapered bearing attached to the support member of said display element so that the tapered wall of said bearing faces said display element, the tapered wall of said bearing being seated in said aperture bearing of said support with the support member extending through said aperture bearing so that said display element is thereby suspended.
- 25 28. A display unit comprising a support, an aperture through said support, a display element including a support member, a tapered bearing attached to the support member of said display element so that the tapered wall of said bearing faces said display element, the tapered wall of said bearing being seated in said aperture in said support with the support member extending through said aperture so that said display element is thereby suspended, and a source of power for rotating said tapered bearing.
- 30 29. A display unit comprising a support, an aperture through said support including a bearing, a display element including a support member, a tapered bearing attached to the support member of said display element so that the tapered wall of said bearing faces said display element, the tapered wall of said bearing being seated in said aperture bearing of said support with the support member extending through said aperture bearing so that said display element is thereby suspended.
- 35 30. A display unit comprising a support, a power driven shaft supported by said support, a housing secured to the end of the shaft, the end of said housing opposite said shaft comprising a cupped tapered bearing having an aperture through the center, a display element including a support member, a tapered bearing attached to the support member of said display element so that the tapered wall of said bearing faces said display element, the tapered wall of said bearing being seated within said housing in said cupped bearing with the support member of said display element extending through the aperture in said cupped bearing so that said display element is thereby suspended.
- 40 31. A display unit comprising a support, an aperture through said support, a tapered bearing seated in said aperture, a power driven shaft supported by said tapered bearing and extending through said aperture, a housing secured to the shaft opposite the support from the tapered bearing, the end of said housing opposite said shaft comprising a cupped tapered bearing having an aperture through the center, a display element including a support member, a second tapered bearing attached to the support member of said display element so that the tapered wall of said bearing faces said display element, the tapered wall of said bearing being seated within said housing in said cupped bearing with the support member of said display element extending through the aperture in said cupped bearing so that said display element is thereby suspended.
- 45 32. A display unit comprising a support, a support bearing having an aperture through the center thereof carried by said support, a display element including a support member, a tapered bearing attached to the support member of said display element so that the tapered wall of said bearing faces said display element, the tapered wall of said bearing being seated in said support bearing with the support member of said display element extending through the aperture therein so that said display element is thereby suspended, one of said bearings being formed of hardened steel and the other of brass.
